(57) CLAIM

The ornamental design for adjustable support for digital camera, as shown and described.

DESCRIPTION

The described adjustable support for digital camera can adjust to support a camera on a tabletop, on a laptop display, or other locations.

FIG. 1 is a perspective view of a adjustable support for digital camera showing our new design;

FIG. 2 is a top plan view thereof;

FIG. 3 is a front elevational view thereof;

FIG. 4 is a left side elevational view thereof;

FIG. 5 is a rear elevational view thereof; and,

FIG. 6 is a bottom plan view thereof.
